United States Patent Office

Des. 204,588
Patented May 3, 1966

204,588

VEHICLE CERTIFICATE HOLDER

Henry C. Laub, 919 6th Ave., Council Bluffs, Iowa

Filed May 17, 1965, Ser. No. 85,302

Term of patent 14 years

(Cl. D1—3)

Fig. 1

Fig. 2

Fig. 4

Fig. 3

Fig. 5

I claim:

The ornamental design for a vehicle certificate holder, substantially as shown.
